UNITED STATES PATENT OFFICE.

EDMUND C. MORGAN, OF MORGAN PARK, ILLINOIS.

MINING-MACHINE.

1,276,248.

Specification of Letters Patent. Patented Aug. 20, 1918.

Application filed June 27, 1910, Serial No. 569,167. Renewed August 4, 1915. Serial No. 43,996.

To all whom it may concern:

Be it known that I, EDMUND C. MORGAN, a citizen of the United States, residing at Morgan Park, in the county of Cook and State of Illinois, have invented certain new and useful Improvements in Mining-Machines, of which the following is a specification.

This invention relates to mining machines, and has for its main general object to provide an improved construction, combination and arrangement of parts in a mining machine whereby the material to be mined may be excavated with facility and dispatch.

15 The primary object of this invention is to provide an improved coöperative arrangement of the cutting, breaking-down and excavating mechanisms.

Another object is to provide improved 20 means for grooving the material to be mined.

Another object is to provide improved means for breaking down the material after it has been grooved.

One of the objects is to provide improved 25 means for mounting the several cutting and breaking down mechanisms.

Another object is to provide improved car loading mechanism coöperative with the mining machine proper.

30 Other and further objects will appear in the specification and be specifically pointed out in the appended claims, reference being had to the accompanying drawings exemplifying the invention, and in which—

35 Figure 1 is a side elevation of a mining machine constructed in accordance with the principles of this invention.

Fig. 2 is a top plan view of the same.

40 Fig. 3 is a medial longitudinal section of the machine taken on the line III—III of Fig. 2.

Fig. 4 is a horizontal section of a portion 45 of the base frame of the machine partly in plan showing the means for regulating the tension of the endless chain grooving device.

Fig. 5 is an enlarged detail section on the line V—V of Fig. 4.

50 Fig. 6 is an enlarged detail section on the broken line VI—VI, Fig. 4.

Fig. 7 is an enlarged section on the line VII—VII of Fig. 3.

Fig. 8 is an enlarged section on the line VIII—VIII of Fig. 3.

55 Fig. 9 is an enlarged detail elevation of the pick-operating mechanism shown in the upper right hand portion of Fig. 3.

Fig. 10 is a detail perspective view partly broken away of one of the forward corner bearing blocks for the endless chain cutter. 60

Fig. 11 is a similar perspective view partly in section of one of the rear bearing blocks of the endless chain cutter.

Fig. 12 is a longitudinal section of the endless chain conveyer removed from the 65 machine.

Fig. 13 is a top plan view of the same partly broken away to show the endless chains.

Fig. 14 is a detail section on the line 70 XIV—XIV of Fig. 13.

Fig. 15 is a side elevation of the frame for mounting the vertical grooving tools and pick mechanisms.

Fig. 16 is a top plan view of the same, 75 parts being removed and broken away to show the operating connections.

Fig. 17 is a side elevation of the same partly broken away to show some of the details of construction in the mechanism for 80 rocking the cutter frame.

Fig. 18 is a detail elevation partly broken away of the feed reversing mechanism.

Fig. 19 is a top plan view of the same.

Fig. 20 is a section on the line XX—XX 85 of Fig. 19.

Fig. 21 is a side elevation of portions of the same mechanism, parts being shown in section.

Fig. 22 is an enlarged detail view of the 90 pick-operating mechanism shown in the upper right hand portion of Fig. 8.

Fig. 23 is a side elevation of the same.

Fig. 24 is a section on the line XXIV— 95 XXIV of Fig. 23.

Fig. 25 is a detail axial section of parts shown in Fig. 23.

Fig. 26 is an end elevation of the parts shown in Fig. 25.

Fig. 27 is a detail fragmentary elevation 100 of a cam for operating the clutch-shifting lever for the pick-operating mechanism.

Fig. 28 is a side elevation of a modified construction for the pick-operating mechanism.

Fig. 29 is a detail cross section of the same, 105 parts being shown in elevation.

Fig. 30 is an enlarged detail sectional view on the line XXX—XXX of Fig. 28.

Fig. 31 is a side elevation of the same 110 parts.

Fig. 32 is a side elevation of a car-loading mechanism.

Fig. 33 is a top plan view of the same,

parts being broken away to show some of the driving connections.

Fig. 34 is an enlarged detail elevation showing an intermediate support for the 5 endless chain conveyer, together with parts of the power transmission for said conveyer.

Referring more specifically to the drawings, and first to Figs. 1, 2, 3, 4, 5, 7 and 8, the main base member of the machine 10 prises a pair of side frames 1 and 2 rigidly connected in front by a transverse plate 3, and in the rear of said base plate by a plurality of cross-bars 4. Said side frames are provided above with guide rails or ridges 15 5 and 6 respectively, upon which is slidably mounted a carriage 7 provided with grooved slides 8 and 9. As shown best in Figs. 5, 7, and 8, the side frames 1 and 2 are provided respectively with feed racks 20 10 and 11, with which mesh the spur gears 12 and 13 for feeding the carriage along said rack in a manner to be hereinafter referred to. Mounted upon the carriage 7 is a horizontal grooving device which preferably 25 consists of an endless chain 14 provided at intervals with grooving tools 15 projecting at different angles from the endless chain 14, as shown in Fig. 5. For suitably mounting the endless chain 14 so that 30 it will stand up under the heavy work which it is called upon to perform, a housing 16 for the endless chain extends on either side of the carriage and across the front, said housing being provided with a T-slot 17 35 opening laterally. Projecting through the lateral opening of the housing 17 are a plurality of shanks 18 for mounting the tools or cutters 15 upon the endless chain 14. As shown best in Fig. 4, the endless chain 14 receives its power from a driving sprocket 18 keyed to a vertical shaft 19, which shaft derives its power in a manner to be herein-after pointed out. In order to provide 40 means for regulating the tension on the endless chain 14, a cross rail 20 connecting the rear ends of the depending housing 16 is provided with a depending lug 21 for supporting a nut 22. Threaded within said nut 22 is an adjusting screw 23 upon which 45 is keyed a worm wheel 24 driven by a worm 25 carried by an adjusting shaft 26 extending transversely across the carriage and provided with squared ends 27 for the reception of a key lever not shown on the drawings. At the forward corners of the housing 16 are provided a pair of bearing blocks 28 of hardened steel, which are secured in position in the chain housing in any suitable manner. At the rear corners of the housing 50 similar bearing blocks 29 are provided, about which the chain 14 passes on its way to and from the sprocket 18. By means of the employment of the blocks 28 in the forward end of the carriage 7 it is made possible 55 to bring the forward end of the end-

less belt conveyer to be hereinafter referred to, nearer to the wall of material which is to be operated upon so that the excavating action of the machine is facilitated and its efficiency greatly enhanced.

The endless belt conveyer shown separate from the machine in Figs. 12, 13 and 14, comprises a pair of endless chains 30, which are oppositely mounted on supporting sprockets 31, 32 carried by transverse shafts 70 33, 34 journaled in the side walls or upright members 35, which, together with a web member 38, forms the chute of the conveyer. Intermediate of the shafts 33 and 34 said side walls 35 are rigidly connected by cross bars or plates 36. Said side walls 35 are provided with inwardly projecting ledges or shields 37 (see Fig. 8) under which is rigidly mounted the supporting web 38, preferably of sheet metal, which extends 80 approximately from the sprocket 31 to the sprocket 32, being supported throughout its length on angle irons 39. The chains 30 are slidably mounted upon the web 38 beneath the overhanging portions of the 85 shields 37, said chains being provided at intervals with conveyer bars in the form of angle irons 40 secured at their ends to the chains 30. It will therefore be seen that as the chains 30 pass upwardly over the web 90 38, the angle bars 40 will engage coal which comes in their way and slide the same upwardly over the said web 38 to the rear of the machine. The shafts 33 and 34 may be 95 rotatably supported within the side walls 100 35 in any suitable manner, but preferably by being journaled within brackets 41 rigidly mounted on the web plate 38. The carriage 7 is provided with laterally disposed standards 42 and 43 having projections or 105 lugs 44 upon which the chute including the endless belt conveyer is adapted to rest in such manner as to be readily removable whenever desired. The endless chains 30 derive their motion through the shaft 34 and 110 sprocket 32 by means of a chain connection 45 (see Figs. 2 and 12) which drives the shaft 34 from a sprocket on the end of a cross shaft 46, which cross shaft is provided on its other end with a sprocket wheel 47 115 connected by a downwardly extending endless drive chain 48 receiving power from the short horizontal shaft 49 which is driven by means of bevel gears 50 from the main drive shaft 51, which in this embodiment of 120 the invention is directly connected to the motor shaft of the motor 52 (see Figs. 2 and 3). Whenever, for any reason, it is desired to dismantle the machine, the chute comprising side walls 35 and web member 125 38 may be removed bodily along with the endless chains 30 with their connections, by first removing the endless chains 45 and 48 from the sprockets on shaft 46.

The motor 52 has an armature rigidly 130

mounted on the drive shaft 51, said drive shaft being provided with a driving pinion 53 meshing with a bevel gear 54 keyed to the upright shaft 19 hereinbefore referred to. As shown more clearly in Figs. 8, 7, 18, 19, 20 and 21, the upright shaft 19 has keyed thereto above the bevel gear 54 a spur gear 55 which meshes with a spur pinion 56, which is free to rotate upon a short upright shaft 57. The spur pinion 58 keyed to the shaft 19 above the gear 55 meshes with the larger gear 59 of a compound gear, a smaller gear 60 of which drives a spur gear 61 freely rotatable on the shaft 57 above the gear 56. The lower end of the shaft 57 is provided with a driving worm 62 meshing with a worm wheel 63, said worm wheel 63 being keyed to a horizontal shaft 64 extending transversely of the machine. Upon each end of the shaft 64 is secured the pinions 12, 13, meshing respectively with the racks 10, 11 rigidly mounted upon each side frame of the base member. Disposed intermediately of the spur gears 56 and 61 and splined to the upright shaft 57 is a clutch 67 (see particularly Figs. 1 and 21) which may be shifted along the shaft 57 into engagement with either of the spur gears 56 or 61. For this purpose a shifting lever 68 mounted upon a pivot 69 is provided with a forked extremity 70 having coaxially mounted pins 71 engaging in a groove 72 in the clutch 67. The lever 68 may be shifted by hand, or, if desired, may be automatically shifted by the travel of the carriage, bringing a depending arm 73 into engagement with a stop 74 mounted on the stationary side frame 2 of the base member. As indicated in dotted lines in Fig. 21, a second stop member 75 may be employed for reversing the travel of the carriage in going in the other direction. The carriage is advanced to its cut when the clutch 67 is in clutch with the larger gear 61, so that the rate of travel is relatively slow on the cutting stroke. The return drive gear 56 is made relatively small and thereby enables a quick return of the carriage.

50 The mechanisms for vertically grooving the coal or other material to be mined and for breaking the same down is preferably mounted on a pair of swinging arms 76, 77 pivotally mounted on short horizontal shafts 78, 79 journaled in suitable standards mounted on the carriage. Upon the outer ends of said swinging arms 76, 77 are journaled suitable grooving saws or cutters 80, which are driven respectively by endless chains 81 each of which is supported about a sprocket rigidly secured to the saw 80 and a second sprocket 82 keyed to one or other of the shafts 78, 79. In order to provide means for driving the shafts 78 and 79, each is provided with a bevel gear 83 keyed to its outer end and meshing with a second bevel gear 84 on the upper end of an extended portion of the vertical shaft 57, and also on a similar shaft 85 on the opposite side of the machine. The shaft 57 derives its power in a manner already pointed out, while the shaft 85 derives its power in a similar manner from the upright shaft 19, which delivers power to the shaft 85 through spur gear 58, idler 86, compound gear 87, 88, and a spur gear 89 keyed to the shaft 85, seen best in Figs. 16 and 19. In order to provide means for rocking the swinging arms 76 and 77, according to the preferred embodiment, driving pins 90 which are eccentrically set on the back faces of the bevel gears 83 respectively, are adapted to slidably engage the slotted arms 91 keyed to a short shaft 92, which also carries a crank arm 93 (see Fig. 17) in the outer end of which is carried a pin 94 engaging in the slotted end of a lever arm 95 rigidly mounted on the side face of the swinging arm 76 or 77 (see also Figs. 2 and 16). It will be understood, therefore, that as the bevel gears 83 are rotated, the arms 76 and 77 are oscillated vertically about their pivotal axis when the saws 80 successively assume the positions shown in dotted lines and full lines in Fig. 15.

55 On each of the swinging arms 76 or 77 is reciprocally mounted an automatic pick or breaking down device consisting of a longitudinal bar 96, which is reciprocably mounted in bearings 97. In the outer end of each rod or bar 96 is a picking tool 98 secured thereto in any suitable manner. In order to provide means for driving the pick 96 to its work, a resilient member in the form of a spring 99 surrounds the bar 96 and is interposed between one of the bearings 97 and a collar 100 secured to the bar 96. A second spring 101 interposed between collar 100 and another one of the bearings 97 serves to take up the jar at the end of the picking stroke. In Figs. 28, 29, 30 and 31, is illustrated a modification of the means for oscillating the swinging arms 76 and 77, which consists of a connecting link 102 connected at one end to the swinging arm 77 and at the other end having a slot 103 which adapts it to slidably and adjustably engage a journal pin 104 which is mounted upon a sliding block 105 within a groove 106 formed in a disk 107. The sliding block 105 is threaded interiorly to adapt an adjusting screw 108 to move it in said slot toward and away from the center to adjust the amplitude of the oscillation of said arm 77. The slotted disk 107 is provided with gear teeth 109 by means of which it may be driven by a spur pinion 110 keyed to a short horizontal shaft 111 upon which is also keyed a worm gear 112 adapted to be driven by a spiral convolute gear 113 formed on the back of a

large bevel gear 114 which may be driven by a bevel pinion 115 from any suitable source of power on the carriage.

- By referring to Figs. 28 to 31, inclusive, it will be seen that the adjustments may be so made as to vary the extent of reciprocation of the vertical kerf cutters 80 while keeping the lower limit of movement thereof substantially the same for every adjustment.
- 10 In order to accomplish this, the nut 179 should be loosened so as to permit free movement of the collar 184 of the journal pin 104 over the boundaries of the slot 103, and to likewise permit free movement of the washer 178. Now, it will be evident that if the arms 77 are held in such position that the vertical kerf cutters will be kept clear of the framework of the machine, the desired adjustment may be made by turning the screw 108 in the sliding block 105 by applying a wrench to the squared head 180. The arms 77 when freed by loosening the nut 179 may be held in their lowermost positions by means of props. When the nut 179 is loosened and the sliding block 105 moved upwardly as viewed in Fig. 30, the arc of swing of the arms 77 will be shortened, while if the sliding block 105 is moved downwardly the arc of swing will be lengthened. This is obvious upon a comparison with Fig. 28, from which it will be seen that the movement of the sliding block 105 changes the radius of the laterally extending journal bearing 181 from the center of the gear 107, which is pivotally supported at 185 in the bracket 186 of the main frame of the machine. It should be noted that the journal bearing 181 is rigidly connected to the sliding block 105, while the journal bearing 104 is freely rotatable on the journal bearing 181 when the nut 179 is loosened. By holding the arms 77 at the desired lower limit of travel and loosening the nut 179, the block 105 together with the journal bearing 181 and sleeve 104 may be moved upwardly or downwardly to the desired position. The nut 179 may then be tightened in position, firmly clamping the collar 184 and washer 178 against the surfaces bounding the slot 103. The sleeve 104 will then be held rigidly in position relatively to the arm 102, but the journal 181 is still freely rotatable in the sleeve 104 to the extent necessary when the gear 107 rotates. The rotary motion of the journal bearing 181 will produce a reciprocatory motion of the pivotal point 183. This will produce a reciprocatory swing of the arms 77 and also the vertical kerf cutters 80, the lower limits of movement of the latter being always the same and in accordance with the adjustments made. To keep the collar 104 in proper position on the journal bearing 181, a cotter pin 182 may be inserted through the

outer end of the journal 181, as shown in 66 Figs. 30 and 31.

In order to provide means for reciprocating the pick bar 96, a gear 116 is journaled above a spur gear 117 and meshes therewith, the gear 117 being keyed to the short horizontal shaft 79 (see particularly Figs. 7 and 9). Coaxially and rigidly connected with the spur gear 116 is a cam 118 which is suitably disposed to impinge a collar 119 carried by the pick rod 96, so that as the cam 118 revolves about its axis, the pick rod is forced rearwardly against the action of the spring 99 and in rearmost position is released by the cam 118 and driven forwardly by the spring 99 into the coal or other material to be mined. In order to widen the range of action of the automatic pick, the pick rod 96 is made oscillatable upon its own axis and upon its rearward end is provided with a hand lever 120, which, while 80 it is freely rotatable about the rod 96, is provided with a spring clutch lever 121, to the depending end of which is pivotally connected a locking pin or bolt 122 (see particularly Fig. 25) slidably mounted in a cylindrical hole in the hub portion 123 of the hand lever 120. Keyed to the pick rod 96 and interposed between the hub portion 123 and the rearmost bearing 97 is a sleeve 124 provided with a radial arm 125 (see particularly Fig. 24). The extremity of the radial arm 125 is rounded or provided with a ball 126 which is adapted to engage in a groove 127 (see also Fig. 27) eccentrically disposed in the side face of a gear 128 which latter 100 is provided with a journal pin 129 projecting laterally therefrom, which pin 129 is journaled in the outer end of a bracket 130. The bracket arm 130 is preferably an integral laterally projecting portion of the rearmost bearing 97. Rigidly mounted on the rearmost bearing block 97 is a second bearing block or pedestal 131 (see particularly Figs. 9, 22, 23 and 24) within which is journaled a short shaft 132 provided on one end 110 with a sprocket wheel 133 over which passes an endless chain 134 supported at its other loop end by a sprocket 135 keyed to the short shaft upon which the spur gear 116 is mounted (see Fig. 7). By this means power 115 is imparted to the short shaft 132 and may be transmitted to the gear 128 for automatically rocking the pick rods 96 by a sleeve gear 136 which is freely rotatable on the shaft 132 and slidable therealong. Said shaft 132 is provided with a tapered enlargement 137 which is adapted to act as a clutch element, the gear 136 being provided in its side face with a similar tapered surface 138 which may be locked with the tapered enlargement 137 when the sleeve gear 136 is reciprocated along the shaft 132. For this purpose a shifting lever 139 is employed,

which may be pivotally mounted on the carriage at any suitable point, and is provided above with a bifurcated portion 140 with suitable pins engaging in a groove 141 in the cylindrical wall of a collar 142 rigidly connected with the sleeve gear 138. A handle 143 formed as an extension of one of the forks of the bifurcated portion 140 serves as convenient means for shifting the lever 139. From this description it will be seen that when the lever 139 is shifted, the sleeve gear 136 is moved over into engagement with the tapered projection 137 and has motion transmitted thereto which it in turn transmits to the gear 128, so that as said gear 128 rotates, the groove or slot 127 therein oscillates on the radial arm 125, and thus causes the pick rod 96 to automatically oscillate upon its own axis without in any way interfering with its other movements.

Referring now more especially to Figs. 1, 2, 3, 32, 33 and 34, the preferred embodiment of a loading conveyer is shown and comprises a base member and an endless chain conveyer. Said base member is constructed of side frames 144 and 145 rigidly connected in any suitable manner and provided at one end with a flat bar or plate 146 connecting the ends of said side frames. Said base member is pivotally mounted to swing about a vertical axis, preferably by extending the side frames 1 and 2 rearwardly and forming thereon a turn table comprising a standard 147 and a bracket 148, which are constructed in a single circular casting. An annular plate 149 recessed along its inner under edge and mounted upon the casting forming the standard 147 and bracket 148 provides a slideway for the flanged annular edge 150 of a cylinder 151 integrally formed with the side frames 144 and 145 of the loading conveyer base member. The loading conveyer is constructed preferably of a pair of girder plates 152 and 153, as shown clearly in Fig. 3, said girder plates being substantially L shaped in cross section with the shorter arm projecting horizontally at the top. These structural sections 152 and 153 are rigidly connected in any suitable manner to the side frames 144 and 145 at the top of the vertical portions of said side frames. As shown in the right hand end of Fig. 3, a pair of plates 154 are mounted within the structural sections 152 and 153 to provide a support for a thin web of sheet metal 155, which extends throughout the length of the conveyer. A pair of endless chains 156 supported by suitable sprockets so as to have one portion of the chain traveling above the web 155 and the other portion below the same are provided with a plurality of transverse angle irons or bars 157 at suitable intervals throughout the length of said endless chains 156, which are adapted to engage

and slide the excavated material over said web 155. To drive the endless chains 156, a sprocket wheel 158 is mounted at each end of the transverse horizontal shaft 159 (see particularly Figs. 33 and 34) to engage the lower portion of each endless chain 156. Keyed to the shaft 159 is a bevel gear 160 (see Fig. 33) which meshes with a second bevel gear 161 on the end of a vertical shaft 162 journaled in a pedestal 163, rigidly supported on the cross bar 146. Keyed to the lower end of the shaft 162 is a sprocket wheel 164 which is driven by an endless chain 165 which at its other end runs about a second sprocket wheel 166 keyed to the upper end of a short vertical shaft 167. Said shaft 167 is journaled in a pedestal 168 integrally formed with the round table hereinbefore referred to. The bevel gear 169 is also keyed to the shaft 167 and is in mesh with a bevel gear 170 on the main drive shaft 51 (see particularly Fig. 3). It will be seen from this description that the loading conveyer is pivotally mounted at the rear end of the base member of the mining machine and projects outwardly therefrom to overhang a car 171, which car may be disposed at any suitable point within the arc of swing of the loading conveyer.

It should be noted that in Fig. 32 the location of the conveyer driving sprocket is such that the length of the conveyer overhanging the mine car is held taut during the operation of the conveyer. This arrangement for driving the conveyer is described and claimed in my co-pending application Serial No. 186,118, filed August 14, 1917, for an improvement in loading machines.

The picking rods 96 are oscillatable to command a greater area of the work, and at regularly recurring intervals, means for accomplishing this purpose is provided by mounting the shifting lever 139 to swing about a pivot 175 (see Fig. 8) disposed intermediately of its ends on the traveling carriage (see also Fig. 1). The lower swinging end 176 of the lever 139 is suitably arranged to be engaged by a lug or projection 177 mounted on the side frame 1 so that as the carriage reciprocates, the lever 139 oscillates to throw the sleeve gear 136 into and out of driven engagement with the shaft 132, whereby the pick rods 96 will be periodically oscillated upon their axes.

What I claim is—

1. In a machine of the character described, the combination with a base frame, of an endless chain-grooving cutter movable on said frame, a carriage reciprocable on the base frame, grooving cutters oscillatably mounted on the carriage, and a picking device reciprocably mounted on said carriage, said picking device being oscillatable on its own axis.

2. In a machine of the character de-

- scribed, the combination with means for making a horizontal groove in the material to be mined, of means for grooving said material transversely to said horizontal 5 groove, a supporting frame and a picking device movable upwardly and downwardly on the frame for breaking down the material, said picking device being reciprocable and oscillatable on its own axis in addition 10 to its upward and downward movement.
3. In a machine of the character described, the combination with a base member, of means for grooving the material to be mined vertically and horizontally, an 15 automatic pick reciprocably mounted above said base member, means for raising and lowering said pick, and means for oscillating said pick on its own axis.
4. In a machine of the character described, the combination with a pivoted cutter frame, of grooving cutters mounted thereon, a pick reciprocably mounted on said frame, said pick being provided with resilient means for driving into the material 20 to be mined, and means for moving the pick to compress the resilient means and for releasing said pick, said pick being oscillatable on its own axis and said cutter frame being provided with means for raising and 25 lowering it on its own pivotal support.
5. In a mining machine, the combination with a base frame adapted to rest on and slide over the floor of a mine chamber, of a reciprocable carriage supported wholly by 30 said base frame and mounted thereon for reciprocating movement longitudinally thereof, a cutter frame pivotally connected to the rear portion of said carriage for up and down movement relatively to said base 35 frame, a kerf-cutter mounted on the forward end of said cutter-frame, means for oscillating said cutter-frame on its pivotal axis to feed said cutter up and down over an upright mine wall in front of the forward end 40 of said base frame, means for actuating said kerf-cutter to cut an upright kerf in a mine wall during such up and down oscillation, a pick reciprocably mounted on said cutter-frame and extending from a position near 45 said kerf-cutter to a position at the rear portion of said carriage, said pick being provided with resilient means tending to force it forwardly into the material to be mined, and cam-operated means for retracting said 50 pick against the action of said resilient means and releasing the pick at the limit of retracting movement to permit said resilient means to cause said pick to strike a blow against the mine wall near the kerf cut by 55 said kerf-cutter.
6. In a machine of the character described, the combination with a reciprocable carriage, of a cutter frame pivotally mounted thereon, cutters mounted in said frame, means for oscillating said cutter frame on its pivotal 60 axis, a pick reciprocably mounted on said cutter frame, said pick being provided with resilient means tending to force it forwardly into the material to be mined, and cam-operated means for retracting said pick, said retracting means being adapted to release the pick at the limit of the retracting movement, said pick being oscillatable on its own axis. 70
7. In a mining machine, the combination with a main frame, of a supplemental frame, a reciprocating pick mounted on said supplemental frame, means for operating said pick, mechanism for vertically oscillating said supplemental frame together with the reciprocating pick thereon, and means for regulating the degree of such oscillation while retaining the lower limit always substantially the same. 75
8. In a mining machine, the combination with a pick machine, of means for operating the same, mechanism for automatically oscillating said pick machine bodily in vertical planes, and adjusting means for regulating the extent of such oscillation while retaining the lower limit always substantially the same. 80
9. In a mining machine, the combination with a pick, of mechanism for operating the same, a support for said pick, mechanism comprising a wheel having an actuating pin projecting therefrom for oscillating said support together with said pick, and means for adjusting the position of said pin radially on said wheel to regulate the extent of oscillation of said pick. 90
10. In a mining machine, the combination with a main frame, of a supplemental frame, breaking down means carried by said supplemental frame, mechanism for continuously and automatically oscillating said supplemental frame together with the breaking down means mounted thereon, and means for regulating the distance of such oscillation while retaining one limit constant. 100
11. In a mining machine, the combination with a main frame, of a supplemental frame pivoted thereto, breaking down mechanism mounted on said supplemental frame, automatic mechanism for operating said breaking down means, and mechanism for automatically continuously oscillating said supplemental frame on its pivot together with the breaking down means during the operation of the latter, and means for regulating the length of the path of oscillation while keeping the lower limit always the same. 110
12. In a mining machine, the combination with a supporting frame, of a main frame, a chain cutter for producing kerfs in a mine wall mounted on said main frame, means for operating said chain cutter, means for feeding said main frame and chain cutter forwardly during the operation of the latter, a supplemental frame pivoted to said main 115 frame. 120
13. In a mining machine, the combination with a main frame, of a supplemental frame pivoted thereto, a chain cutter for producing kerfs in a mine wall mounted on said main frame, means for operating said chain cutter, means for feeding said main frame and chain cutter forwardly during the operation of the latter, a supplemental frame pivoted to said main 125 frame. 130

- frame, breaking down means carried by said supplemental frame, means for continuously and automatically oscillating said supplemental frame together with the breaking down means during the feeding forward of said main frame, and means for continuously operating said breaking down means during the operation of said chain cutter.
13. In a mining machine, the combination with a chain cutter for producing a kerf at the base of a mine wall, of means for operating said chain cutter, means for feeding said chain cutter forwardly during operation, vertical kerf cutters for producing kerfs in the mine wall approximately above the lateral limits of the base kerf, breaking down means for operating on the mine wall between the vertical side kerfs, means for operating said vertical side kerf cutters and said breaking down means while said base kerf cutter is being operated, and means for lifting and lowering both the breaking down means and the vertical side kerf cutters.
14. In a mining machine, the combination with an under cutter, of a pick machine, mechanism for operating said pick machine, means for automatically oscillating said pick machine as a whole continuously, a platform for receiving directly the material broken down by said pick machine, and means for conveying the broken down material from said platform where received toward the rear of the mining machine.
15. In a mining machine, the combination with an elongated main frame, of a supplemental elongated frame pivoted at its rear portion on a substantially horizontal axis to said elongated main frame and extending longitudinally of the latter toward the front end thereof, a pick machine mounted on said supplemental elongated frame for movement up and down therewith in position for operation on an upright mine wall near the forward end of said elongated main frame, automatic means for continuously oscillating said pick machine by moving said supplemental frame up and down to secure arcuate feeding movement of said pick machine on a comparatively long radius, and mechanical means between said main and supplemental frames for operating said pick machine while being oscillated up and down along an upright mine wall over such arc of long radius.
16. In a mining machine, the combination with a supporting frame, of a pick machine pivoted to said supporting frame on a substantially horizontal axis and extending therefrom in a general horizontal direction for operation on an upright mine wall over an arc having a long radius, means for automatically oscillating said pick machine as a whole continuously up and down relatively to said supporting frame and on said horizontal axis to secure feeding movement

of said pick machine along an upright mine wall over an arc of long radius, and means wholly mechanical for operating said pick machine while thus being oscillated up and down over such arc of long radius.

17. In a mining machine, the combination with a pick machine, of means for operating the same, and gearing comprising a circular groove with the end of a crank movable therein for oscillating said pick machine.

18. In a mining machine, the combination with a picking tool, of an actuating rod connected thereto, a spring associated with said rod, cam mechanism for compressing said spring and suddenly releasing the same to freely act on said rod and cause the picking tool to strike a blow at a mine wall to break down material therefrom, a cushioning spring on said rod, a frame for supporting said rod and comprising spaced-apart sliding bearings for said rod and to act as abutments for said springs, a collar fixed to said rod in a position between said springs, and means independent of said cam mechanism and said springs for oscillating said rod.

19. In a mining machine, the combination with an oscillatable picking tool, of a rod carrying the same, a spring associated with said rod, means for compressing said spring and suddenly releasing the same, an additional spring associated with said rod to act as a cushion against movement of said picking tool beyond a predetermined distance in its forward movement toward breaking down material, and mechanism independent of said compressing means for oscillating said picking tool.

20. In a mining machine, the combination with an oscillatable picking tool, of a rod carrying the same, two sliding bearings for said rod, a collar fixed to said rod between said bearings, an actuating spring between said collar and one of said bearings, a cushioning spring between said collar and the other bearing, means for compressing said actuating spring and suddenly releasing the same to cause said picking tool to strike a blow against a mine wall to break down material therefrom and means for oscillating said picking tool.

21. In a mining machine, the combination with a pointed picking tool, of a rod for carrying the same, a spring associated with said rod, involute cam mechanism for compressing said spring and suddenly releasing the same to cause said picking tool to strike a blow against an upright mine wall to break down material therefrom, and means operable independently of the operation of said cam mechanism for moving said rod in an arc on its own axis during the operation of said picking tool.

22. In a mining machine, the combination with a picking tool of a holder therefor, an

- actuating rod, a connection between said actuating rod and said holder at substantially right angles to said rod to offset said picking tool in a line parallel to said rod 5 and at a predetermined distance therefrom, spaced apart bearings for said rod, a collar fixed to said rod between said bearings, an actuating spring between said collar and one of said bearings, a cushioning spring 10 between said collar and the other of said bearings, an additional collar fixed to said rod, a pivoted involute wiper cam associated with said additional collar, means for continuously rotating said involute cam to cause 15 the same to engage said additional collar and move the rod and picking tool back to compress said actuating spring and then suddenly releasing said spring to cause the same to operate said picking tool to strike 20 a blow against the mine wall and repeating such reciprocation of the picking tool, and automatic mechanism for oscillating said rod to vary the position of said picking tool through the arc of a circle.
- 25 23. In a mining machine, the combination with a base frame, of a reciprocable carriage mounted thereon, an under-cutting kerf-cutter mounted on said carriage, spaced-apart upright kerf-cutters mounted 30 on said carriage, a pick machine mounted on said carriage, means for operating said pick machine between said side cutters and above said under-cutter, means for automatically oscillating said pick machine as a whole 35 continuously up and down, a platform for receiving the broken-down material directly from its native position in the upright mine wall operated on by said pick machine, and means for conveying the broken-down material 40 from said platform where received toward the rear of the mining machine.
24. In a mining machine, the combination with supporting framework, of an under-cutting kerf-cutter mounted thereon, spaced-apart upright kerf-cutters mounted on said framework to coöperate with said under-cutting kerf-cutter to cut a U-shaped kerf in an upright mine wall, a traveling conveyer having superposed portions traveling 45 in opposite directions from a forward receiving position within the boundary of the under-cutting kerf-cutter and extending rearwardly on an upward incline toward loading position with a free and unobstructed space above the conveyer for the passage of large blocks of material from the mine wall toward loading position, spaced-apart pick machines mounted laterally of the conveyer without obstructing the passage 55 way of said conveyer but comprising picking tools each arcuately movable toward and from the upright planes of the side kerfs, means for operating said pick machines, and mechanism for arcuately adjusting said picking tools to break down 60
- onto the receiving end of said conveyer substantially all of the material within the boundary of said kerfs.
25. In a mining machine, the combination with framework comprising an elongated chute, of a traveling conveyer extending along said chute and comprising superposed portions traveling in opposite directions, said chute having a free and unobstructed space above the same for the passage of large blocks of material moved by said conveyer toward loading position, a pick machine mounted laterally of said conveyer chute and comprising a picking tool supported by a rod in a position offset radially from the axis of said rod for operation in directions substantially parallel to said rod approximately above the forward receiving end of said conveyer, means for arcuately adjusting the position of said picking tool to command a wide area of material of an upright mine wall near the receiving end of said conveyer, and means for operating said pick machine percussively in each of its adjusted positions to dislodge the material from the mine wall onto said conveyer.
26. In a mining machine, the combination with an elongated frame, of a conveyer mounted thereon and comprising superposed portions traveling in opposite directions with a free and unobstructed space above the same for the passage of large blocks of material, spaced-apart pick machines mounted at the sides of said conveyer without obstructing the space above the same but comprising picking tools extending to positions upwardly in front of the receiving end of said conveyer, a motor mounted under the rear portion of said conveyer, power transmission mechanism under said conveyer and extending to the sides thereof to operate said pick machines, and additional power transmission mechanism extending to the rear of said pick machines at the sides of said conveyer for automatically oscillating the picking tools arcuately.
27. In a mining machine, the combination with a supporting frame, of spaced-apart bearings having transverse axes, of spaced-apart gears mounted in such bearings, spaced-apart pick machines connected for operation to said spaced-apart gears, power transmission mechanism connected to both of said gears for operating said pick machines, means for tilting said pick machines up and down on the axes of said bearings, and a conveyer extending along said supporting frame between said pick machines and said bearings with a free and unobstructed space above the conveyer for the passage of large blocks of material dislodged by said pick machines.
28. In a mining machine, the combination with an elongated main frame comprising 120

- 5 a longitudinal chute, of a conveyer extending along said chute and having a free and unobstructed space above the same for the passage of large blocks of material, a bracket mounted on said frame at one side of said conveyer chute and having a bearing extending transversely of the conveyer, a short shaft in said bearing, a pick machine extending along one side of said conveyer
- 10 chute without obstructing the passageway along said chute but extending to a position near the forward end of said chute for acting on an upright mine wall to dislodge material therefrom onto the receiving end of
- 15 said conveyer, power transmission gearing connected to one end of said short transverse shaft, mechanism connected between the other end thereof, and such pick machine for operating the latter, and means
- 20 for pivotally supporting said pick machine for up and down tilting movement on the axis of said short shaft.
- 25 29. In a mining and loading machine, the combination with an elongated base frame, of a carriage reciprocably mounted on said base frame, an undercutting chain kerf-cutter mounted on said carriage and movable bodily therewith, an elongated chute mounted on said carriage and extending
- 30 from a forward receiving position approximately within the boundary of said undercutter, upwardly on an incline toward loading position with a free and unobstructed space above the same for the passage of
- 35 large blocks of dislodged material, an endless conveyer mounted on said carriage and extending along said chute, said conveyer having superposed portions traveling in opposite directions, spaced-apart supplemental
- 40 frames pivotally mounted to the rear portion of said carriage and extending forwardly at the sides of said chute to positions
- approximately above the forward end of said undercutter, spaced-apart pick machines one mounted on each of said spaced-apart supplemental frames to extend along the sides of said chute, spaced-apart upright kerf-cutters mounted on the forward ends of said supplemental frames for operation in upright spaced-apart planes approximately intersecting the lateral edges of the under kerf, means for operating said pick machines in the space between the planes of said upright side kerf-cutters, means for operating said side kerf-cutters, means for operating said under kerf-cutter, means for moving said spaced-apart supplemental frames together with the pick machines and the side kerf-cutters mounted thereon in up and down directions without interfering with the operation of said pick machines and of said side kerf-cutters, said moving means being mounted on said carriage and extending to said spaced-apart supplemental frames and said operating means being also mounted on said carriage and extending to said pick machines and said side kerf-cutters without obstructing the space above said chute and conveyer, a motor mounted on said carriage, and means for feeding said carriage together with the parts mounted thereon along said base frame to feed the under cutter, the side cutters and the pick machines into the mine wall while moving the conveyer longitudinally with the under cutter.
- In testimony whereof I have signed my name to this specification, in the presence of two subscribing witnesses, on this 21st day of June A. D. 1910.
